This invention relates to a new and original design for carpets and similar fabrics; and it consists in the novel grouping and configuration of parts hereinafter more fully described.

The accompanying photograph illustrates a face view of a carpet having my new design.

B is a stripe containing an ornamentation of a series of rectangular figures, a, set alongside or upon each other like bricks, each figure a bearing ornamentation on its surface. The band b separates the stripe B from the stripe C, and contains an ornamentation of a series of figures set side by side.

The stripe C is ornamented with flower-like figures, with squares having flower ornamentation thereon set at intervals.

The stripe D contains an ornamentation of flower bunches, e and d, set alternately along the stripe, and of a vine-like figure, c, running along the top thereof. Below the stripe D is the band f, containing an ornamentation of a series of figures partly composed of fine dots set close together. The band g, below the band f, contains a series of rectangular panels, each 30 containing a semicircular ornament.

I claim—
